PENCIL

Earle Roscoe Weaver, Princeville, Ill.

Application March 25, 1940, Serial No. 325,866

7 Claims. (Cl. 120—18)

My invention relates to new and useful improvements in pencils.

An important object of my invention is to provide a pencil which includes a mechanism adapted to advance or retract the eraser or the lead.

Another object of my invention is the provision of a pencil of the above-mentioned character wherein the operating parts of the mechanism 10 are associated with the casing of the pencil in a manner whereby the writer may actuate the same without releasing the normal writing grip on the pencil.

Still another object of my invention is the provision of a pencil of the above-mentioned character that will greatly expedite the performance of duties which require the taking of rapid dictation, such as news or court reporting, and the like, and that will relieve all who use the same from the necessity of interrupting their writing to further advance the lead.

Yet another object of my invention is the provision of a pencil of the above-mentioned character that includes a novel means for advancing or retracting the eraser whereby the necessity for removing or disengaging parts of the pencil is eliminated.

Other objects and advantages of my invention will be apparent during the course of the following description.

In the drawings, forming a part of this specification, and wherein like numerals are employed to designate like parts throughout the same,

Figure 1 is a longitudinal sectional view showing parts in section and parts in elevation, of a device embodying my invention,

Figure 2 is a view similar to Figure 1, but showing parts broken away and parts in section,

Figure 3 is a transverse sectional view taken 40 on the line 3—3 of Figure 1,

Figure 4 is a perspective view of the guide tube and illustrating the manner in which the same slidably supports the lead carrying sleeve and the lead expelling follower bar,

Figure 5 is a front elevation of my device,

Figure 6 is a longitudinal sectional view of a modified form of my invention,

Figure 7 is a longitudinal sectional view taken 50 on the line 7—7 of Figure 6, and showing parts in elevation, parts broken away and parts in section,

Figure 8 is a fragmentary perspective view of the feeding guide sleeve and illustrating its association with the driven pinion embodying a 55 part of my invention.

Figure 9 is a longitudinal sectional view, showing parts in elevation and parts broken away, of an eraser advancing and retracting mechanism constructed in accordance with my invention, and

Figure 10 is a transverse sectional view taken on the line 10—10 of Figure 9.

In the accompanying drawings, wherein for the purpose of illustration, is shown a preferred embodiment of my invention, the numeral 15 10 designates a tubular casing formed with reduced externally screw-threaded annular shanks 16 and 17 at its opposite ends. The shank 17 threadedly receives the internally screw-threaded end 18 of the head 19 which, as clearly illustrated in 15 Figure 1, is formed with a tapered lower end 20. The upper portion of the head is centrally recessed, as at 21, and the lower portion thereof is solidly constructed and formed with an axial bore 22 of a size to slidably but snugly receive a 20 pencil lead 23. The apex of the head is provided with a plurality of annularly spaced indentations 23' which extend into the lower end of the bore 22 and engage the periphery of the lead to hold the same in a selected extended position; the upper end of the bore 22 is enlarged and internally 25 screw-threaded to receive the threaded shank portion 24 of the cupular fitting 25. The fitting 25 receives and supports the lead advancing and retracting mechanism 26, the distal end of 30 which extends substantially beyond the end 16 of the casing and into the cap 27 which screw-threadedly engages the annular shanks 16 of the casing in a manner to have a smooth peripheral union therewith.

The guide tube 28 comprises a part of the lead advancing and retracting mechanism and is provided with a longitudinal slot 29 and a screw-threaded lower end 30 fixedly received by the internal bore 31 of the fitting. The feeding 40 guide sleeve 32 is mounted for rotation about the tube 28 and extends for substantially its entire length; the lower end thereof is fixedly associated with a ratchet pinion 33 which, in turn, is supported by the inner annular shoulder 34 defined 45 by the enlarged upper portion 35 of the fitting and the upper end thereof is fixedly connected to a knurled actuating nut 36. The feeding guide may be formed in any suitable manner, as by helically forming a flat strip of metal around the 50 tube 28 and with the convolutions thereof spaced from each other to define a helical guide track 37 in the manner illustrated in Figure 1.

Figure 6 illustrates another form of feeding 55 guide 38 which comprises an elongated metallic

strip of substantially U-shaped formation in cross-section, which strip is wound around the tube 28 and with the open side thereof in confronting relation with the tube. In this form of feeding sleeve the guide track 40 is defined by the space enclosed by the U-shaped band 38.

In both forms of guide sleeves the lowermost portion 39 of the guide track is disposed for a short distance in a plane extending transversely of the longitudinal axis of the sleeve for a purpose presently to be described in detail. As will be readily apparent from an inspection of Figures 1 and 6, the guide track 37 in Figure 1 is open; the protective sleeve 41 is positioned there-around in circumferentially spaced relation thereto and with the lower end thereof threadedly received by the fitting 25 in slightly spaced relation with the ratchet pinion 33 in a manner to hold the same seated against but freely rotatable on the shoulder 34. The form of guide track illustrated in Figure 6 is closed and does not require the application of a protective sleeve; the lock-nut 42 is, therefore, screw-threadedly received by the fitting 25 in a manner to hold the ratchet pinion 33 seated against the shoulder 34.

The lead receiving sleeve 50 is slidably arranged within the guide tube 28 and is adapted to accommodate the upper end 51 of the lead within the lower portion thereof. The upper portion of the sleeve is provided with a laterally extending lug 52 which extends through the slot 29 and into the guide track 37 or 40 of the feeding guides 32 or 38. The follower or expelling bar 53 is slidably received by the sleeve 50 and with the lower end 54 thereof normally bearing against the upper end 51 of the lead. The upper end of the follower is formed with a laterally extending lug 55 which extends through the slot 29 and into the guide track 37 or 40 one convolution above the lug 52.

The fitting 25 is formed with an internally recessed, tangentially extending boss 43, which recess 44 opens directly against the peripheral teeth of the pinion 33. The upper portion of the head 19 is formed with an opening 45 laterally of the boss 43, whereby the pawl element 46 may extend through the opening to be slidably accommodated by the boss and whereby the end 47 thereof extending into the recess 44 may be moved into engagement with the teeth of the pinion. A fingerpiece 48 comprises an essentially spherically curved oval plate member which receives the pawl 46 substantially centrally thereof. The crown portion of the plate extends beyond the periphery of the head and the peripheral edge thereof is normally seated against the portion of the inner wall of the head circumjacent the opening by the coil spring 49 interposed between the plate and the boss 43.

In operation, the lead carrying sleeve 50 and the follower 53 may be moved axially within the guide sleeve 28 by rotating the feeding sleeve 32 or 38 about the guide tube. The lugs 52 and 55 of the sleeve and follower will move within the guide track 37 as the feeding sleeve is rotated and will consequently be raised or lowered within the sleeve in accordance with the direction of rotation of the feeding sleeve. Rotation of the sleeve in an anti-clockwise direction will cause the sleeve and follower to be retracted within the sleeve and this operation is accomplished by removing the cap 27 and manually rotating the feeding sleeve by means of the knurled nut 36. The lead 23 may then be inserted within the guide sleeve 28 through the bore 22 in the head and

into the lower portion of the lead carrying sleeve 50. As illustrated in Figure 3, the feeding sleeve may be rotated in a clockwise direction by manually pressing the fingerpiece 48 in a manner to move the end 47 of the pawl into engagement with the teeth of the ratchet pinion 33. The above operation will impart a step by step rotation to the sleeve in a manner to axially move the lead carrying sleeve and to advance the lead 38.

When the lug 52 of the lead carrying sleeve has reached the lower terminus of the guide track, it will be moved in a plane transversely of the longitudinal axis of the pencil for a limited distance. During such transverse movement, the lug 55 of the follower bar will be further advanced within the lead carrying sleeve in a manner to eject the remaining fragment of lead carried by the sleeve.

The hereinabove described arrangement particularly adapts itself to a pencil construction permitting the taking of rapid dictation in that the lead may be advanced without necessitating the writer releasing his normal writing grip. The fingerpiece 48 is positioned in a manner to be normally readily accessible to the index finger of the writer, whereby he may actuate the pawl by moving the finger a slight distance laterally of the normal writing position and into engagement therewith. The operation may be performed with the writing hand and make it unnecessary for the writer to raise the pencil from the paper and actuate remote portions of the pencil in order that the lead may be advanced.

Figures 9 and 10 illustrate a modification of the cap 27 in that a mechanism 57 is incorporated therewith to advance or retract an eraser 58. In order that the eraser advancing and retracting mechanism may be incorporated within the structure hereinbefore described, the upper end 40 of the casing 15 is made to extend substantially the entire length of the lead advancing and retracting mechanism 26, and the cap 27 is threadedly associated therewith in the manner hereinbefore described. The mechanism 57 is fixedly positioned by the support 73 and the component parts comprising the same are similar in their construction and association to the parts described for the lead advancing and retracting mechanism except that the unit is of substantially lesser length and the feeding sleeve 38 is made to assume a substantially greater pitch. The eraser receiving sleeve 50 is of substantially greater diameter in order to accommodate the relatively larger eraser 58 and the other constituent parts are relatively enlarged in direct proportion therewith.

The ratchet pinion 33 is fixedly associated with the feeding sleeve 38 and the wall of the cap is provided with a pair of diametrically opposed openings 59 and 60 arranged laterally of the pinion. An arcuate bar 61 is secured to the inner periphery of the cap intermediate of the openings 59 and 60 by the screws 62, or the like, and the extending ends thereof are bent inwardly 63 between the openings and the ratchet pinion whereby the enlarged portions 63 and 64 may slidably support the pawl elements 65 and 66. The outer ends of the pawls carry fingerpieces 67 and 68, which fingerpieces are associated with the wall of the cap in the manner described for the association of the fingerpiece 48 with the wall of the head 19. Coil springs 69 and 70 are interposed between the fingerpieces 67 and 68 and bearings 63 and 64 in a manner to normally 75

hold the pawls disengaged from the pinion 33. Actuation of the fingerpiece 67 will rotate the pinion 33 in a clockwise direction to advance the eraser 58 and advancement of the eraser will open the panel 71 hingedly closing the end of the cap and normally held in a closed position by the springs 72. When it is desired to retract the eraser within the cap, the fingerpiece 68 may be actuated to rotate the pinion in an anticlockwise direction and, as the eraser is retracted within the cap, the spring 72 will effect the closure of the end panel 71.

It is to be understood that the form of my invention, herewith shown and described, is to be taken as a preferred example of the same, and that various changes in the size, shape and arrangement of parts may be resorted to without departing from the spirit of my invention, or scope of the appended claims.

20 Having thus described my invention, I claim:

1. A pencil comprising a casing having an opening in the side wall thereof, a lead advancing and retracting mechanism mounted for rotation within said casing, gear means carried by the mechanism adjacent the casing opening, and an actuator means cooperatively associated with the gear means for imparting a step by step rotation thereto, parts of said actuator being manually accessible through the opening in the side wall of the casing.

25 2. A pencil comprising a casing having an opening in the wall thereof and adjacent the writing end of the pencil, a lead advancing and retracting mechanism rotatably mounted within said casing, said mechanism being rendered operative by rotation thereof, and an actuator means for imparting rotation to the mechanism, parts of said actuator means being arranged adjacent the opening in the casing wall for manual actuation, whereby the said actuator may be rendered operative by the fingers of the writer and without releasing the normal writing grip on the said pencil.

30 3. A pencil comprising a casing having an opening in the wall thereof adjacent the writing end of the pencil, a lead advancing and retracting mechanism rotatably mounted within said casing, gear means fixedly carried by the mechanism adjacent the opening in the casing wall, a pawl extending through the opening and engageable with the said gear means, and a fingerpiece carried by the outer end of the pawl, said fingerpiece having a peripheral engagement with the inner wall of the casing circumjacent the opening, whereby the pawl may be manually moved into engagement with the gear means to impart a step by step rotation thereto and without releasing the normal writing grip on the pencil.

35 4. A pencil comprising a casing having an opening in the wall thereof adjacent the writing end of the pencil, a lead advancing and retracting mechanism rotatably mounted within said casing, gear means fixedly carried by the mechanism adjacent the opening in the casing wall, a pawl extending through the opening and engageable with the said gear means, a fingerpiece carried by the outer end of the pawl, said fingerpiece normally having a peripheral engagement with the inner wall of the casing circumjacent the opening, and resilient means normally holding the pawl disengaged from the gear means whereby

the pawl may be manually moved into engagement with the gear means against the action of the said resilient means to impart a step by step rotation thereto and without releasing the normal writing grip on the pencil.

5 5. A pencil comprising a casing having a tapered working end, an axial bore and a side opening adjacent the said working end, a longitudinally slotted tube fixedly mounted axially of the casing, a helical guide mounted for rotation about the tube, gear means rotatably carried by the tube and fixedly secured to the said guide, a lead receiving sleeve axially movable within said tube and having a lug extending laterally through the slot and received by the said guide, a follower received by the upper end of the sleeve and having a lug extending laterally through the slot and received by the guide, a pawl extending through the side opening of the casing and engageable with the gear means, and spring means normally holding the pawl out of engagement with the said gear means, whereby the pawl may be manually moved into engagement with the gear means to impart a step by step rotation thereto and without releasing the normal writing grip on the pencil.

10 6. In a pencil including a tubular casing, a lead advancing and retracting mechanism associated with the casing comprising a slotted tube fixedly arranged within the casing and in register with the lead discharge bore of the casing; a helical guide mounted for rotation about said tube, a portion of the lower convolution of the guide being arranged in a plane extending transversely of the axis of the guide; a lead receiving sleeve axially movable within said tube and having a lug extending laterally through the slot and received by a portion of the guide; a follower received by the sleeve and normally engaging the lead contained thereby, said follower having a lug extending laterally through the slot and received by another portion of the guide; and means to rotate the said guide to simultaneously move the sleeve and follower within the tube, whereby continued rotation of the guide after engagement of the sleeve lug with the mentioned transverse portion of the guide will effect movement of the follower axially within the sleeve to eject the lead contained thereby.

15 7. In a pencil, the combination with a casing of a tubular cap having one end adapted to be detachably connected to the casing; a longitudinally slotted tube fixedly mounted axially within said cap; a helical guide mounted for rotation about said tube; a tubular sleeve axially slidable within said tube and having a lug extending laterally through the slot and received by the guide; a follower arranged axially of and received by the sleeve and having a lug extending laterally through the slot and received by the guide; gear means carried by the said guide; a pair of pawl elements extending through openings in the cap and arranged to engage the gear means in a manner to differentially rotate the same; and spring means normally holding the pawls out of engagement with the gear means, whereby one of the said pawl elements may be manually actuated to rotate the gear means in one direction and the other of the said pawl elements may be manually actuated to rotate the said gear means in the opposite direction.

EARLE ROSCOE WEAVER.
